UNITED STATES PATENT OFFICE.

CHESTER T. ALLCUTT, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTING DEVICE.

1,323,238.

Specification of Letters Patent.

Patented Dec. 2, 1919.

Application filed September 1, 1917. Serial No. 189,345.

To all whom it may concern:

Be it known that I, CHESTER T. ALLCUTT, a citizen of the United States, and a resident of Wilkinsburg, in the county of Allegheny and State of Pennsylvania, have invented a new and useful Improvement in Circuit-Interrupting Devices, of which the following is a specification.

My invention relates to circuit-interrupting devices and particularly to means for automatically interrupting electric circuits under predetermined conditions.

One object of my invention is to provide a quick-acting tripping device for a circuit interrupter that shall be energized partly from the circuit to be protected and partly from an auxiliary circuit only when the current traversing the circuit to be protected exceeds a predetermined value.

Another object of my invention is to provide a device of the above indicated character that shall have a relatively large operating torque, be simple and inexpensive to construct and effective in its operation.

My copending application Serial No. 189,344, filed September 1, 1917, discloses means for quickly energizing a trip coil from the circuit to be protected. However, it is frequently necessary to cause the tripping device to exert a relatively high prolonged torque to insure rapid and effective operation of the interrupter.

In view of the above, I provide a circuit interrupter, a trip coil therefor, a series transformer that is connected between the circuit to be protected and the trip coil, and a spark gap that is connected in the trip-coil circuit for operatively connecting the trip coil to the circuit under predetermined conditions. A spark gap and a condenser are operatively connected between the trip coil and an auxiliary circuit. With this arrangement, when the first spark gap breaks down, or discharges, sufficient voltage of relatively steep wave front is impressed across the trip coil to break down the other spark gap and to discharge the condenser that is connected to the auxiliary circuit. Thus, a relatively large operating current is insured and, consequently, quick and effective operation of the trip coil is obtained.

The single figure of the accompanying drawing is a diagrammatic view of an electric circuit embodying my invention.

An alternating-current electric circuit 1

is provided with a circuit interrupter 2 having a trip coil 3 that is adapted to be actuated to trip the interrupter under predetermined conditions in the circuit.

One terminal of the trip coil 3 is connected to one terminal of the secondary winding 4 of a transformer 5, the primary winding 6 of which is connected in series with the circuit 1. The other terminal of the trip coil 3 is connected to one terminal 7 of a spark gap 8, the other terminal 9 of which is connected to the other terminal of the secondary winding 4. A condenser 10 of relatively small capacitance is connected across the terminals of the winding 4 and is adapted to discharge when sufficient voltage is impressed across the winding 4 to cause the spark gap 8 to break down. The secondary winding 4 of the transformer 5 is adapted to be normally open circuited and to have a potential that is substantially proportional to the current traversing the primary winding 6.

An auxiliary circuit 11, that is supplied with current from a source 12 of direct current, is provided with an electrolytic condenser 13 or other condenser of relatively large capacitance one terminal of which is connected to one conductor of the circuit 11 and the other terminal of which is connected, through a relatively high resistance resistor 14, to the other conductor of the circuit 11. One terminal 15 of a spark gap 16 is connected to one terminal of the condenser 13 and the other terminal 17 of the spark gap 16 is connected to one terminal of the trip coil 3. The other terminal of the trip coil 3 is connected to the other terminal of the condenser 13.

When an excessive overload traverses the circuit 1, sufficient voltage is induced in the winding 4 of the transformer 5 to break down the spark gap 8 and permit the condenser 10 to discharge. The condenser 10 is of such capacitance that the voltage across the trip coil 3 has a steep wave front and is of such value as to cause the spark gap 16 to be broken down. The initial rush of current from the circuit 1, if insufficient to operate the movable member 18 of the trip coil 3, will be supplemented by the discharge of the condenser 13. Thus, a relatively large operating current is supplied to the trip coil 3 to insure its relatively quick and effective operation, under all conditions.

My invention is not limited to the specific device illustrated, as it may be variously modified without departing from the spirit and scope of the invention as set forth in the appended claims.

I claim as my invention:

1. In an electric circuit, the combination with a tripping electromagnet, a spark gap and means for operatively connecting the electromagnet and the spark gap to the circuit, of an auxiliary source of current, and means for causing the auxiliary current to traverse the electromagnet only when a potential is impressed across the electromagnet by reason of the discharge of the spark gap.
2. In an electric circuit, the combination with a trip coil, and a spark gap in series therewith adapted to discharge when a predetermined current traverses the circuit, of an auxiliary source of current, and means for causing current from the auxiliary source to traverse the trip coil only when the spark gap is discharged.
3. In an electric circuit, the combination with a trip coil and means for energizing the trip coil from the circuit under predetermined conditions, of an auxiliary source of current, and means for causing the auxiliary current to traverse the trip coil only when a predetermined potential obtains across the trip coil by reason of its energization from the circuit.
4. In an electric circuit, the combination with a trip coil and means connected to the circuit for impressing a high-frequency voltage upon the trip coil when an overload obtains thereon, of an auxiliary source of current, and means for causing the auxiliary current to traverse the trip coil under predetermined conditions in the trip coil.
5. In an electric circuit, the combination with a circuit interrupter, a trip coil therefor, a spark gap in circuit with the trip coil and means for breaking down the spark gap when the current traversing the circuit exceeds a predetermined value, of an auxiliary

source of current, and a spark gap operatively connected between the trip coil and the auxiliary source of current that breaks down when the potential across the trip coil exceeds a predetermined value.

6. In an electric circuit, the combination with a trip coil and means for operatively connecting the trip coil to the circuit under predetermined circuit conditions, of an auxiliary means for assisting in energizing the trip coil after it has been connected to the circuit.

7. In an alternating-current circuit, the combination with a circuit interrupter, a trip coil therefor and means for operatively connecting the trip coil to the circuit under predetermined conditions, of a direct-current circuit, and means for operatively connecting the trip coil to the direct-current circuit when the alternating-current voltage across the trip coil exceeds a predetermined value.

8. In an alternating-current circuit, the combination with a circuit interrupter, a trip coil therefor and means for causing an oscillating current to traverse the trip coil from the circuit under predetermined conditions, of a direct-current circuit, and a spark gap connected between the trip coil and the direct-current circuit and adapted to break down when the potential across the trip coil exceeds a predetermined value.

9. In an alternating-current circuit, the combination with a circuit interrupter, a trip coil therefor and means for causing an oscillating current to traverse the trip coil from the circuit under predetermined conditions, of a direct-current circuit, a condenser connected across the direct-current circuit, and a spark gap for so connecting the direct-current circuit to the trip coil that an effective operating current will traverse the trip coil under predetermined conditions.

In testimony whereof I have hereunto subscribed my name this 21st day of August, 1917.

CHESTER T. ALLCUTT.
